UNITED STATES PATENT OFFICE

110,322

DESIGN FOR A CLOTHES DRYING FRAME

Harriet Holder French, Newport, R. I.

Application April 27, 1938, Serial No. 76,766

Term of patent 14 years

To all whom it may concern:

Be it known that I, Harriet Holder French, a citizen of the United States, of 1 Red Cross Avenue, in the city of Newport, county of Newport, and State of Rhode Island, have invented a new, original, and ornamental Design for a Clothes Drying Frame, of which the following is a specification, reference being had to the accompanying drawing, forming part thereof.

Fig. 1 is front view of a clothes drying frame, the rear view being the same as the front view, and Fig. 2 is a top plan view.

I claim:

The ornamental design for a clothes drying frame, as shown.

HARRIET HOLDER FRENCH.
